ATTORNEY

UNITED STATES PATENT OFFICE

HENRY MALLARD, OF STOCKTON, CALIFORNIA.

STARTING DEVICE FOR VEHICLE-MOTORS.

1,335,345.

Specification of Letters Patent. Patented Mar. 30, 1920.

Application filed July 28, 1918. Serial No. 313,896.

To all whom it may concern:

Be it known that I, HENRY MALLARD, a citizen of the United States, residing at Stockton, in the county of San Joaquin, 5 State of California, have invented certain new and useful Improvements in Starting Devices for Vehicle-Motors; and I do declare the following to be a full, clear, and exact description of the same, reference being had to the accompanying drawings and 10 to the characters of reference marked thereon, which form a part of this application.

This invention relates to improvements in devices for starting the engine of motor vehicles, and is particularly adapted to be used on those of the Ford type.

The principal object of the invention is to produce a device for the purpose which will be operable from the driver's seat, and 20 by means of which the engine may be turned over two complete revolutions with every single movement of the operating means.

A further object is to produce a device which will be concealed under the hood of 25 the engine and which may be installed on the engine without necessitating any structural changes therein.

A further object of the invention is to produce a simple and inexpensive device and 30 yet one which will be exceedingly effective for the purposes for which it is designed.

These objects I accomplish by means of such structure and relative arrangement of parts as will fully appear by a perusal of 35 the following specification and claims.

In the drawings similar characters of reference indicate corresponding parts in the several views.

Figure 1 is an outlined side elevation of a 40 Ford engine, showing my improved starter installed in connection therewith.

Fig. 2 is a front elevation of a gear and ratchet drum.

Fig. 3 is a sectional view of the same.

Fig. 4 is a detached view of a clutch mechanism for throwing the actuating mechanism into connection with the engine shaft.

Referring now more particularly to the 50 characters of reference on the drawings, the numeral 1 denotes the engine and 2 the crank handle having the usual ratchet clutch 3 on the inner end thereof, the handle being

adapted to move toward the engine so that the clutch 3 will engage a pin on the forward 55 end of the crank shaft.

This latter feature is not shown, as it is the usual construction on engines of the type mentioned.

A bracket 4 is mounted on the engine at a 60 suitable point adjacent its forward end, and to this bracket is bolted a vertical drum or casing 5, centrally in which is mounted a shaft 6. On this shaft, outside the casing 65 and to the rear thereof, is turnably mounted a sprocket wheel 7, having spring dogs 8 thereon adapted to engage a ratchet wheel 9 secured to the shaft 6. A coiled spring 9^a is secured to the casing and to the sprocket wheel 9 in such a manner that said wheel 70 will always return to its normal position.

A gear 10 is keyed to the shaft 6 inside the casing 5, meshing with a pinion 11 which in turn meshes with an internal gear 12 turnably mounted on the shaft. 75

A small pinion 13 meshes with the gear 12 only, the shaft 14 of which pinion being mounted in the casing 5 and projecting through the forward end thereof, having on such projecting portion a chain sprocket 15 80 from which a chain 16 leads to a sprocket 17 loosely mounted on the shaft 2^a of the crank handle member 2 forward of the clutch 3.

On the forward face of the sprocket wheel 17 are ratchets 18 adapted to engage with a 85 ratchet member 19 secured to the shaft 2^a when the same is moved to engage the clutch 3 thereof with the engine shaft.

The above described mechanism is actuated by the driver of the vehicle in the following manner:

A chain 20 is normally wound on the sprocket wheel 7 and secured thereto at one end so as to permit of the rotation of said wheel for approximately one revolution. 95 The outer end of this chain is secured to a cable 21 which passes around a pulley 22 secured to the engine frame and thence to the lower end of a pedal lever 23 pivoted to the floor of the vehicle adjacent the dash-board and in a suitable location.

Thus by pushing the pedal forward with the foot, the chain 20 unwinds from the sprocket wheel 7, causing the same to rotate, and so ultimately imparting motion to 105 the sprocket wheel 15, the ratio of the va-

rious gears being such that the speed of the sprocket wheel 15 will be double that of the initial wheel 7.

When the pressure on the pedal is released, the spring 9^a will cause the chain 20 to wind up on the sprocket wheel 7 and the pedal 23 to return to its normal position.

In order to throw the clutch ratchets 18 and 19 into engagement and move the crank handle shaft 2^a to engage the engine shaft, I provide a push rod 24 attached at one end to the pedal 23 above the pivotal point thereof. The other end of the rod has a pair of spaced eyes 25 through which projects a rod 26 connected at its other end to one end of a bell crank 27 pivoted to the engine base, which in turn is operatively connected to the sleeve of the ratchet member 19.

A spring 28 is interposed on the rod 26 between one of the eyes 25 and a collar 29 on the rod so that when the rod 24 moves forward with the movement of the pedal 23, the first result is the compression of the spring 28 until the strength thereof is sufficient to cause the bell crank 27 to move the shaft 2^a to engage the clutch 3 thereof with the engine shaft and also the ratchets 18 and 19, which latter action of course places the sprocket wheel 17 in operative connection with the engine shaft.

After said ratchets and clutch are once in engagement any further forward movement of the rod 24 merely causes the spring 28 to be further compressed, thus preventing bending or breaking the rod 26 or any of the parts connected thereto.

When the pressure on the pedal is released, the ratchets 18 and 19 are of course disengaged, both by the action of the spring 28 and by that of the spring normally provided on the crank handle shaft which tends to normally hold the same out of engagement with the engine shaft.

From the foregoing description it will be readily seen that I have produced such a device as substantially fulfills the object of the invention as set forth herein.

While this specification sets forth in detail the present and preferred construction of the device still in practice such deviations from such detail may be resorted to as do not form a departure from the spirit of the invention, as defined by the appended claims.

Having thus described my invention what I claim as new and useful and desire to secure by Letters Patent is:

1. A starter for vehicle motors comprising a sprocket wheel loosely mounted on

the crank handle shaft of the motor, a casing secured to the motor, a sprocket wheel mounted in the casing and operatively connected to the first named sprocket wheel, a ratchet wheel mounted on the casing and connected with the sprocket wheel therein with a predetermined ratio of rotation, and a common means operable by the driver of the vehicle for actuating the ratchet wheel to turn the sprocket wheels and at the same time moving the crank handle shaft into operative connection with the sprocket wheel thereon and with the motor crank shaft.

2. A starter for vehicle motors comprising a sprocket wheel loosely mounted on the crank handle shaft of the motor, a casing secured to the motor, a sprocket wheel mounted in the casing and operatively connected to the first named sprocket wheel, a ratchet wheel mounted on the casing and connected with the sprocket wheel therein with a predetermined ratio of rotation, a pedal lever mounted on the floor of the vehicle within reach of the feet of the driver, means connected to the pedal and to the ratchet wheel whereby the same may be turned through a complete revolution with each full forward movement of the pedal, and means operatively connected to the pedal and the crank handle shaft whereby the said shaft may be moved into connection with the motor crank shaft and with the sprocket wheel on the crank handle shaft simultaneously.

3. A starter for vehicle motors comprising a sprocket wheel loosely mounted on the crank handle shaft of the motor and adapted to be placed in turning connection with such shaft when the latter is moved into connection with the motor crank shaft, a casing secured to the motor, a sprocket wheel mounted in the casing and operatively connected to the first named sprocket wheel, a ratchet wheel mounted on the casing, gearing in the casing between the ratchet wheel and the sprocket wheel to give the latter a predetermined ratio of turning relative to the former, and means operable by the driver of the car whereby the ratchet wheel may be turned through one revolution with each movement of such operating means.

In testimony whereof I affix my signature in presence of two witnesses.

HENRY MALLARD.
